UNITED STATES PATENT OFFICE.

WILLIAM J. KEENE, OF CHICAGO, ILLINOIS, ASSIGNOR TO CHICAGO SPRING BUTT COMPANY, OF CHICAGO, ILLINOIS.

SPRING-HINGE.

1,111,157.

Specification of Letters Patent.

Patented Sept. 22, 1914.

Application filed January 3, 1911. Serial No. 600,484.

To all whom it may concern:

Be it known that I, WILLIAM J. KEENE, a citizen of the United States, and a resident of Chicago, county of Cook, and State of Illinois, have invented certain new and useful Improvements in Spring-Hinges, of which the following is a full, clear, and exact description.

The improvement relates to means for fastening spring hinges to doors and the like and more particularly to fastening means for double acting spring hinges of the type set forth in a prior application filed in the United States Patent Office by George W. Schuster and myself on January 3, 1910, Serial No. 535,951.

The invention seeks to provide simple and effective means by which spring hinges may be readily and quickly secured to the cut-away corners of doors and the like and also seeks to provide simple and effective means for adjusting the hinge relatively to the door, so that, where the hinge is double acting, the door may be accurately centered in closed position.

The invention consists in the features of improvement hereinafter set forth, illustrated in the preferred form in the accompanying drawing and more particularly pointed out in the appended claims.

In the drawings, Figure 1 is a longitudinal section of the hinge and fastening means therefor shown as applied in position upon a door. Fig. 2 is a view in elevation of the hinge frame and fastening plate. Figs. 3 and 4 are sections on the lines 3—3 and 4—4 of Figs. 1 and 2.

The hinge members are similar to those set forth in the prior application above referred to. The hinge frame comprises upper and lower parallel bars 1 and 2, the upper bar having a downturned portion 3 at one end and the lower bar having an upturned portion 4 at the opposite end. The end of the bar 1 and of the portion 3 thereon are provided with lugs 5 which extend through openings in the bar 2 and end portion 4 and these lugs are headed over to secure the parts of the frame together. A pair of transverse plates 6 and 7 are arranged between the two bars and are secured to position by lugs 8 thereon, extending through openings in the bars 1 and 2 and headed over, as shown.

A floor plate 9 is provided with a fixed

vertical post 10 which is journaled at its upper and lower ends in the bars 1 and 2. A bushing 11 is preferably interposed between the post and the lower bar 2 and a suitable ball bearing 12 is preferably interposed between the upper end of the post and the bar 1. The bolt 13 extends through openings in the transverse plates 6 and 7 and its inner end is provided with a head or yoke 14 having a longitudinal slot 15 therein, through which the post 10 extends. At its inner end the yoke 14 is provided with depending lugs or abutments 16 which are arranged to engage a pair of eccentrically disposed stops or rollers 17 mounted on opposite sides of the lower portion of the post. A spring 18, coiled about the bolt 13, extends between a transverse plate 6 and an adjusting collar 19 on the outer end of the bolt. With this construction, one of the abutments 16 and one of the stops or rollers 17 cooperate to compress the spring 18 when the door is swung in one direction and the other abutment and stop or roller cooperate to compress the spring when the door is swung in the opposite direction, so that the spring acts to return the door and hold it in normal central position.

The hinge frame comprising the bars 1 and 2 and parts carried thereby, is adapted to be seated in a recess or cut-away portion at the lower corner of a door 21. The fastening means for holding the hinge frame in position comprises a longitudinally extending strip or plate 22 which is provided with openings for receiving screws 23 and which is adapted to be secured in position by the screws to the edge of the recess in the corner of the door, as shown. At its outer end the bar 22 is provided with a depending portion 24 having rearwardly projecting lugs or ears 25 with notches 26 above the ears to receive the outer end of the bar 1 of the frame. The downturned portion 3 of the bar 1 is narrower than the top of the bar, so that it can pass between the ears or lugs 25 when the end of the bar 1 is engaged with the notches 26.

The opposite end of the fastening plate or bar 22 is provided with downturned lugs 27 having notches 28 in their inner edges. The side edges of the bar 1 of the hinge frame at its inner end is provided with notches 29 arranged to receive the lugs 27 of the fastening plate and with lugs or

shoulders 30 adapted to enter the notches 28 of the lugs.

In mounting the hinge upon a door, the lower corner of the door is first cut away to form a suitable recess or rabbet for receiving the hinge frame and fastening plate. The fastening plate 22 is then secured in position by the screws 23. The hinge frame is then placed in position with the outer end of the bar 1 extending slightly within the notches 26 and with the lugs 27 of the fastening plate extending within the notches 29 at the inner end of the bar 1. Then, by shifting the hinge frame longitudinally in outward direction, the end of the bar 1 is completely engaged with the notches 26 and the lugs 30 are completely interlocked with the notches 28 of the lugs 27. The interlocking parts or lugs of the frame and fastening plate are thus arranged to be engaged by the longitudinal movement of the hinge frame.

Means are provided for securing the hinge frame against longitudinal movement to hold the interlocking parts in engagement, and such means preferably comprises two adjusting screws 31 which extend loosely through openings in the lugs 25 and are threaded into a suitable opening in the depending portion 3 of the bar 1. These screws not only serve to secure the hinge frame against longitudinal movement, but also to adjustably connect the outer ends of the hinge frame and fastening plate, so that these parts may be adjusted relative to one another in lateral direction to accurately center the door in closed position. This lateral adjustment is permitted, since the end portion 3 of the hinge frame is narrower than the space between the ears or lugs 25. By loosening one of the adjusting screws and tightening the other, the door to which the parts are fastened may be moved to a slight extent in one or the other direction, after the floor plate 9 has been fixed in position to thereby accurately center the door in closed position.

The open sides of the hinge frame are closed by cover plates 32 which are secured to the sides of the door by screws 33. These cover plates are provided with openings 34 opposite the heads of the adjusting screws 31, so that the adjustment of the parts may be effected without removing the cover plates.

It is obvious that numerous changes may be made in the details set forth without departure from the essentials of the invention as defined in the claims.

60 I claim as my invention:—

1. In a spring hinge, the combination with a hinge frame adapted to be seated in a recessed corner of a door, of a fastening plate adapted to be secured to the edge of the recess, said frame and fastening plate

having interlocking lugs arranged to be engaged by the movement of said frame relatively to said fastening plate and fastening devices directly connecting said frame to said plate to thereby hold said lugs interlocked, substantially as described. 70

2. In a spring hinge, the combination with a hinge frame, adapted to be mounted in horizontal position in the recessed corner of a door, of a fastening plate adapted to be 75 secured to the horizontal edge of the recess, said plate having depending notched lugs at its opposite ends and said frame having interlocking parts arranged to be engaged with said notched lugs in the longitudinal 80 movement of said frame and fastening devices for holding said frame against longitudinal movement, substantially as described. 85

3. In a spring hinge, the combination with a hinge frame adapted to be seated in the recessed corner of a door, of a fastening plate adapted to be secured to the edge of the recess, said plate having depending notched lugs at its opposite ends and said frame having interlocking parts arranged to be engaged with said notched lugs by the longitudinal movement of said frame, and screws directly connecting said plate and said frame to hold the latter against longitudinal movement, substantially as described. 90

4. In a double acting spring hinge, the combination of a floor plate having a post and stops on opposite sides of the post, a hinge frame pivotally engaging said post, a spring actuated plunger mounted in said hinge frame and engaging said stops, a fastening plate adapted to be secured to a door, and connecting devices between the 100 opposite ends of said hinge frame and said plate, the connecting devices at one end of said frame and plate being adjustable, substantially as described. 105

5. In a double acting spring hinge, the 110 combination of a floor plate having a post and stops on opposite sides of the post, a hinge frame pivotally engaging said post, a longitudinally movable spring actuated plunger mounted in said hinge frame and engaging said stops, a fastening plate adapted to be secured to the door, said hinge frame and said plate having interlocking lugs at one end arranged to be engaged by the relative movement of said frame and plate, and fastening screws for adjustably connecting the opposite ends of said frame and plate, substantially as described. 115

6. In a double acting spring hinge, the 1 combination with a hinge frame, of a fastening plate adapted to be secured to a door, said frame and plate having interlocking lugs arranged to be engaged by the longitudinal movement of said frame, and means 1 for holding said frame against longitudinal

movement and for adjusting the same, laterally, substantially as described.

7. In a double acting spring hinge, the combination with a hinge frame, of a fastening plate adapted to be secured to a door, said plate having projecting notched lugs at its opposite ends, said frame having interlocking parts arranged to be engaged with said lugs by the longitudinal movement of 10 said plate, and adjusting screws extending

through the lugs at one end of said plate and engaging said frame for holding the latter against longitudinal movement and for laterally adjusting one end of said frame relatively to said plate, substantially as de- 15 scribed.

WILLIAM J. KEENE.
